UNITED STATES PATENT OFFICE.

JOHN GOTTR, OF BRIGHTON, ENGLAND, ASSIGNOR TO COMMERCIAL CABLE COMPANY,
OF NEW YORK, N. Y., A CORPORATION OF NEW YORK.

WORKING SUBMARINE CABLES.

1,122,383.

Specification of Letters Patent. Patented Dec. 29, 1914.

Application filed May 17, 1913. Serial No. 768,336.

To all whom it may concern:

Be it known that I, JOHN GOTTR, a subject of the King of Great Britain, and resident of Hove, Brighton, England, have invented 5 certain new and useful Improvements in Working Submarine Cables, of which the following is a specification.

In the drawing, Figure 1 is a diagrammatic view showing the invention applied 10 to a duplex cable system; Fig. 2 a detail view of a simple relaying means; and Fig. 3 a detail diagrammatic view of the receiving apparatus.

This invention relates to improvements in 15 systems of electric signaling in which the international Morse code is used in the transmission of messages over long submarine cables, in place of the recorder code heretofore used, whereby cable operation is simplified and uniformity of working with land 20 lines is established.

It is well known that reversed currents sent rapidly through a long submarine cable are the most effective in definition as received at the distant end of the cable—each 25 following current having the effect of neutralizing the preceding one.

In carrying out this invention every unit 30 of each letter is formed by a reversed current, so that in no case during transmission does an impulse of current of one polarity follow one of the same polarity. At the receiving end of the cable these reversed currents form units of letters and are trans- 35 formed in a simple manner, so that the signals come out in Morse characters, as if received through a short land line and are, therefore, easy to read and transcribe. This method of signaling is fully described in my 40 Patent No. 1,056,533, dated March 18, 1913.

To obtain the reversals of polarity of the current to the line for each unit of a letter or signal with absolute uniformity and certainty, I make use of a condenser placed 45 in circuit with the windings of a polarized relay and charged by the signaling current. When the signaling key is released this condenser is discharged to earth through the polarized relay, the armature of which is 50 thus actuated.

The sending of the impulses through the cable is effected by the use of an ordinary Morse key precisely as in operating ordinary telegraph land lines. Of course, automatic 55 transmitters may be employed if desired;

and these automatic transmitters may be of any desired construction, and may be operated by perforated tapes or otherwise, for the transmission of the well known Morse code. It is also to be understood that the 60 signals transmitted by this apparatus may be translated from a land line to a cable, or from the cable to a land line by any suitable translating means maintaining the alternation of current impulses. 65

At the receiving end of the line means are provided for transforming the reversals of current into the common Morse code. This is accomplished by means of a repeater whose contact when at rest occupies a neutral position between two contact plates which are connected to a local battery in circuit with a local repeating or recording device. In this form of repeater or receiver the contact point completes the local circuit without regard to the polarity of the received current impulse so that the local circuit through the local receiving or repeating instrument is completed for each received current impulse without regard to the polarity of said received current impulse. It follows, therefore, that the received impulses are transformed in the local circuit into ordinary Morse code signals. It also follows that these received impulses may be repeated into 85 connected cables or land lines by the instruments in the local circuit if that be desired, all of which is fully pointed out in my patent referred to herein. 75

The invention will now be described with 90 reference to the accompanying drawings.

In Fig. 1, *a* designates a cable; *b* the artificial cable used in duplex working; *c*, *c'* condensers; *d* the transmitting key; *f* the front contact of the key; *g* the local battery 95 connected to the front contact of the key and to earth at *g'*. In the local circuit is arranged a transmitting sounder *T S*. The apex of the bridge between the cable and the artificial line is connected by wire *e* to the 100 contact arm *t* of said sounder. The back contact *s'* of the transmitting sounder is connected to earth at *g''* and the front contact *s''* is connected to the tongue or contact arm *h²* of the polarized relay *h*. Upon depressing the key *d* and thereby closing the local circuit the contact arm *t* of the transmitting sounder is brought against the front stop to thereby connect the cable and artificial line to the contact arm of the polarized 105 110

relay. Upon raising the key *d* and thereby interrupting the local circuit the contact arm of the transmitting sounder is moved against its back stop and the cables 5 charged to earth at *g*''.

A split battery *l l'* is connected to earth at *l''*, and one side of said battery is connected to the front stop *h*¹ of the polarized relay, the opposite side of the split battery 10 being connected to the back contact *h*² thereof. It is manifest that as the contact arm of the polarized relay moves from one stop to the other the polarity of the current to the cables will be reversed, a negative 15 current being placed on the line when the contact arm is against the stop *h*² of the relay, and a positive current being placed on the line when the contact arm is against stop *h*¹.

20 In the local circuit is arranged a condenser-controlling relay *C R*, the contact arm *r'* of which is connected to a condenser *C*, said condenser being also connected to earth. The back contact *i* of the condenser-controlling relay is connected to the coil of 25 the polarized relay said coil being also connected to earth at *i'*. The front stop of said condenser-controlling relay is connected to the tongue or contact arm of the polarized relay, so that the said arm completes the circuit from one or the other side of the split battery *l l'* to the condenser *C*, when the local circuit is closed through the key *d*. This results in charging the condenser each 30 time the key *d* is depressed, and, of course, each time a signal impulse is sent over the cable *a*. When the local circuit is interrupted by raising the key *d*, the contact arm of the condenser-controlling relay 35 moves to the rear contact thereof, thereby connecting the condenser *C* to the coil of the polarized relay so that the condenser will discharge to earth through said coil. Each discharge of the condenser through 40 the relay coil is opposite in polarity to the preceding discharge, so that the contact arm of the polarized relay is swung from one stop to the other by each condenser discharge. This results in a change 45 of polarity of current to the line for each key operation, that is to say, for each key closure. When the key *d* is depressed the battery *l* or *l'* is connected to the line and to the condenser *C*. When the key is 50 opened the condenser will discharge through the windings of the polarized relay and the tongue of the relay will then be thrown against the other stop of the polarized relay thereby reversing the polarity of the current to the front stop *s''* of the transmitting sounder *T S* and consequently to the line when the key is again depressed or closed. It is manifest that the same cycle of operations follows each depression and raising of 55 the sending key. The result of this is that 60

the current impulse sent to the line at each key operation will be opposite in polarity to the previously sent current impulse. It is, therefore, clear that in operating the key for sending Morse code signals each signal 70 unit impulse, whether it be a dot or a dash, will be opposite in polarity to the preceding signal unit impulse and, therefore, no two succeeding signal unit impulses will be of the same polarity. 75

Fig. 2 simply illustrates how the tongue *T* of a relay connected to a land line or short cable takes the place of the contact arm *t* of Fig. 1. It also illustrates how the rocking contact bar of a Wheatstone transmitter is connected in place of the key to send automatically into the cable, the upper two contacts of the transmitter only being used. 80

Fig. 3 represents the apparatus used at 85 the receiving or terminal end of the cable. The two metal plates *v* and *v'* are separated by an insulator *y*. The contact making tongue *V* is actuated by an attachment to the signal coil of a recorder which coil is in circuit with the cable. Arriving signals move this tongue from zero to *v* or *v'* according to the polarity of the arriving current. For the purpose of this invention the two metal plates are connected together by 90 the wires at *W* and are in circuit with the local battery, etc. The instrument at *Z* may be a Morse recording instrument, a sounder or relay or other instrument. It will be clearly seen that rapid reversals will be indicated by the sounder, for example, as dots or dashes, as if made on one contact only, as in ordinary Morse working. 100

I desire it understood that I consider any means for transmitting impulses of current 105 to the line the equivalent of the transmitting key, and that where I use the term key it is, of course, to be understood that I include any equivalent device or apparatus. In relaying from one cable into another, of 110 course, the relay armature becomes a transmitting key; likewise in any arrangement of apparatus in which the impulses of current are sent automatically, the automatic transmitting means becomes the key. 115

The receiving apparatus of Fig. 3 is shown in connection with the transmitting apparatus of Fig. 1. It is manifest that the received signal impulses of current of alternating polarity are reproduced in the local 120 circuit controlled by the receiving relay, (and in which local circuit the coils of the receiving instrument *z* or of the relay are arranged), as impulses of like polarity, precisely as the signals are produced in an ordinary telegraph system with a Morse key. 125

What I claim is:

1. A system of cable working comprising a cable, a sending key, a polarized relay, a battery, a condenser, and means whereby 130

- upon the opening of the key the relay will be operated by the discharge of the condenser to reverse the connections of the battery to the line.
- 5 2. A system of cable working comprising a cable, a sending key, a polarized relay, a condenser, means whereby upon the opening of the key the relay will be operated by the discharge from the condenser to change the 10 polarity of the current to the line, and means at the receiving or terminal end of the line for receiving the signal impulses irrespective of their polarity.
- 15 3. A condenser, a line, a sending key, a polarized relay, a split battery, means whereby the condenser is charged when the sending key is closed and the battery connected to the line, means whereby the discharge from the condenser will pass through the 20 windings of the polarized relay and reverse the position of the tongue of said relay when the sending key is opened, and means whereby the reversal of position of the relay tongue will reverse the battery connections 25 to the line.
4. A system of cable working comprising a cable, a sending key, a polarized relay, a condenser, and means whereby the cable charging current will charge the condenser, said means serving to reverse the position of the relay tongue when the key is opened and the condenser discharged.
- 30 5. A system of cable working comprising a cable, a transmitting means for sending impulses of current into the cable, a condenser, means whereby the cable charging current will charge the condenser during the transmission of each signal impulse and
- means whereby when the transmitting means is opened and the cable charging current is interrupted the discharge from the condenser will reverse the polarity of the line current for the next succeeding impulse. 40
6. A system of cable working comprising a cable, a transmitting means for sending impulses of current into the cable, a locally arranged capacity, means whereby the cable charging current will charge the local capacity during the transmission of each signal impulse and means whereby when the transmitting means is opened and the cable charging current is interrupted the discharge from the local capacity will reverse the polarity of the line current for the next 45 succeeding impulse. 50
7. A system of cable working comprising a cable, a transmitting means, a condenser and means operated by the discharge of the condenser upon the opening of the transmitting means to change the polarity of the 60 current to the line.
8. A system of cable working comprising a cable, a transmitting means, a condenser, means operated by the discharge of the condenser upon the opening of the transmitting means to change the polarity of the current to the line, and means at the receiving or terminal end of the line for receiving the signal impulses irrespective of their 65 polarity. 70

In testimony whereof I hereunto affix my signature in the presence of two witnesses.

JOHN GOT.
